UNITED STATES PATENT OFFICE

106,647

DESIGN FOR A COLOGNE BOTTLE OR SIMILAR ARTICLE

John D. Buckingham, Evanston, Ill., assignor to
Lucien Lelong, Inc., Chicago, Ill., a corporation
of Illinois

Application August 25, 1937, Serial No. 71,319

Term of patent 7 years

To all whom it may concern:

Be it known that I, John D. Buckingham, a citizen of the United States and a resident of the city of Evanston, county of Cook, and State of Illinois, have invented a new, original, and ornamental Design for a Cologne Bottle or Similar Article, of which the following is a specification, reference being had to the accompanying drawing, forming a part thereof.

On the drawing:

Figure 1 is a side elevational view of the cologne bottle showing my new design.

Figure 2 is a top view thereof.

I claim:

The ornamental design for a cologne bottle or similar article as shown.

JOHN D. BUCKINGHAM.
